DESIGN.

C. WIPFLER & W. J. KEEP.

STOVE.

No. 16,677.

Patented May 4, 1886.

UNITED STATES PATENT OFFICE.

CHARLES WIPFLER AND WILLIAM J. KEEP, OF DETROIT, MICHIGAN.

DESIGN FOR A STOVE.

SPECIFICATION forming part of Design No. 16,677, dated May 4, 1886.

Application filed September 8, 1884. Serial No. 142,549. Term of patent 7 years.

To all whom it may concern:

Be it known that we, CHARLES WIPFLER and WILLIAM J. KEEP, of Detroit, in county of Wayne and State of Michigan, have invented and produced a new and original Design for Stoves, of which the following is a specification, reference being had to the accompanying photographic illustration, forming a part thereof.

10 Our design consists of the ornamentation of the various parts, as herein specified.

Our design also consists of a new top ornament, not including the finishing urn on top of this ornament.

15 A represents the foot section. Above the foot is a skirt with a configuration and ornamented as shown.

C represents the flue base, at the bottom of which is a quarter round molding. Above 20 this comes a nearly vertical narrow flat, a more sloping flat; above this is another quarter-round surmounted by an ogee, and then a flat surmounted by a curve to join the next section.

25 D represents the ash-pit section, which is covered by a former design patent, now owned by the Michigan Stove Company, Detroit, Michigan.

E represents a ring having a quarter-round 30 edge, surmounted by a flat and round, which separates the sections D and F.

F represents the doors, which form a fire-pot section, usually called "lower mica section." Each one of these doors is provided 35 with six rectangular openings, designed to be filled with mica. The bars composing these doors are half-round in section.

G represents a ring of the same general configuration as the ring E, and which separates the sections F and H.

40 H represents what is usually termed the "upper mica section," and is composed of doors which have nine openings for mica. The bars forming this door are of half-round section.

45 I represents the top plate of the stove. At the rear of this top is a collar, R.

J K L M represents a top ornament for a stove, composed of a ring, J, of a smaller diameter than the top of the stove I, a perpendicular section, K, a projecting edge, L, and a cover, M.

The upper extra ornament, N, may be used in connection with our ornament below it, or not, as may be desirable. The ring J has an ornament near its upper edge. The section K has a series of ornaments around its circumference, and located about midway between the top and bottom. The ring L is smooth, and the covering portion is ornamented with a series of points above the smooth portion, and finished by a rough surface at its center.

What we claim as new is—

1. In a design for a stove, the shape and ornamentation of the leg-section A B, as shown.

2. In a design for a stove, the shape and ornamentation of the section F, as shown.

3. In a design for a stove, the shape and ornamentation of the section H, as shown.

4. In a design for a stove, the shape and ornamentation of the top ornament J K L M, as shown.

5. In a design for a stove, the shape and ornamentation of the ring J, as shown.

6. In a design for a stove, the shape and ornamentation of the perpendicular section K, as shown.

7. In a design for a stove, the shape and ornamentation of the cover M, as shown.

8. The design of a stove, consisting of the projecting base with round edges, the round edges, E, G, and I, sections between said rings and the flue Q and P, the pipe-collar R, and the top ornament J K L M, as shown.

CHARLES WIPFLER,
WILLIAM J. KEEP.
